ROOF STRUCTURE

Howard J. Dinstbir, Butler, Pa.

Application December 9, 1931. Serial No. 579,843

3 Claims. (Cl. 296—137)

The present invention relates broadly to the art of building construction, and more particularly to an improved roof structure adapted for automotive and other vehicles.

For purposes of a better understanding of the invention, it will be hereinafter described and illustrated in connection with an automobile top, it being understood, however, that the utility of the invention is not thus limited. In automobiles as at present constructed, the roofs, particularly of closed automobiles, such as sedans and coupes, are not in keeping with the remainder of the car structure either as to inherent strength, durability or appearance. Such roof structures ordinarily comprise metallic quarter panels extending either entirely around the car and serving to define the plane of the roof proper, or extending around all sides thereof except the front. In any case, such quarter panels, being formed of metal, may be finished in keeping with the remainder of the car structure so that their appearance and durability conform to the remainder of the car. The principal portion of the roof, however, is ordinarily constructed of a fabric, or treated material of special composition having a materially less durability than the remainder of the car, and not adapted to a finish of lasting characteristics. As the overall height of cars has been decreased, the roof structure becomes more easily visible to the pedestrian, and is usually characterized by a center panel or panel-like structure of dull appearance.

Not only does the present day roof construction detract from the general appearance of the automobile, by reason of its inherent characteristics, but it is objectionable by reason of its susceptibility to comparatively easy destruction. Thus, in the case of parked cars it not infrequently happens that holes are burned in the roofs, through the head lining and frequently the upholstery, since the fabric compositions in present day roofs are of a combustible nature.

It is one of the objects of the present invention to provide an improved roof construction which will have characteristics in keeping with those of the remainder of the car both as to appearance, durability and susceptibility to a lasting finish.

In the accompanying drawings there are shown by way of illustration only, certain preferred embodiments of the present invention. In the drawings:

Figure 1 is a top plan view of a typical form of car roof constructed in accordance with the present invention;

Figure 2 is a transverse sectional view on the

line II—II of Figure 1, looking in the direction of the arrows;

Figure 3 is a detail sectional view, on an enlarged scale, along the line III—III of Figure 1;

Figure 4 is a view similar to Figure 3 illustrating a modified embodiment of the invention;

Figure 5 is a view similar to Figures 3 and 4, illustrating still another form of the invention;

Figure 6 is a plan view of a blank adapted to form a roof structure of the character illustrated in Figure 4 of the drawings;

Figure 6a is an inverted plan view of one corner of the blank when folded up to its final shape;

Figure 6b is a detail sectional view along the line VI—VI of Figure 6a, looking in the direction of the arrows;

Figure 7 is a view similar to Figure 6, illustrating a portion of a blank adapted to form a roof of the construction illustrated in Figure 5;

Figure 7a is an inverted plan view of a portion of the blank of Figure 7 when folded to final shape;

Figure 7b is a detail sectional view on the line VII—VII of Figure 7a, looking in the direction of the arrows; and

Figure 8 is a detail sectional view on an enlarged scale along the line VIII—VIII of Figure 1.

In the construction of car roofs, and particularly where utilized for automotive vehicles, there are certain fundamental requirements which must be satisfactorily met. In the first place the roof must be of sufficient inherent rigidity to maintain itself under the different road conditions to which it is subjected. To this end, and in order to accommodate the weaving of the car body, it has been considered necessary that the roof be of more or less flexible material. In accordance with the present invention, the flexible material is replaced by sheet metal of suitable thickness having a certain amount of inherent resiliency, but preferably braced to preclude possibility of distortion. The weaving of the car, and any difference between expansion and contraction of the car body and the car roof, are absorbed by means of a special mounting by means of which the metallic roof is carried.

In the form of the invention illustrated in Figures 1, 2, 3 and 8, there is shown an automobile roof including quarter panels 2 extending around three sides thereof and serving to define the plane of the roof proper and connect the entire roof structure to the car body 3 indicated in dotted lines in Figure 2. These quarter panels, which may be pressed from a continuous sheet or from a series of strips suitably secured together, usually

provide substantially horizontally extending inwardly projecting flanges 4 joined to the car body, and vertically extending flanges 5 defining the plane of the roof proper and the area or 5 extent thereof.

In accordance with the form of the invention illustrated in these figures, I provide a strip of yielding or resilient material 6, herein illustrated as molded rubber, extending completely around 10 the roof opening defined by the quarter panels. Such material, which must serve as a sealing material and shock absorbing material, is preferably constructed to provide a substantially vertically extending outer wall 7 adapted to abut against 15 the inner side of the flange 5, and with a projection 8 adapted to underlie the lower edge of such flange. At its upper portion there is provided a projecting lip 9 adapted to extend outwardly over the quarter panel an appreciable distance and 20 thus preclude the passage of water upwardly along the quarter panel and thence downwardly between the flange 5 and the material 6.

At its opposite side the strip 6 is formed with a second projection 10, similar to the projection 25 8, and adapted to underlie the lower edge of a downwardly projecting stiffening flange 11 lying against the inner surface 12 of the strip 6 and welded or otherwise secured, as indicated at 14, to a metallic roof 15. The roof is of such dimensions 30 as to overlie the strip 6 and the lip 9, and preferably terminate substantially flush with the outer edge of the lip and thus form a durable and attractive finish with the quarter panel, and serve as confining and protecting means for the 35 sealing strip. The roof panel is also preferably of such contour as to subject at least the lip portion 9 to a considerable degree of compression, thus more effectively sealing the same against the quarter panel 2.

40 The parts having been assembled in the desired relationship, they may be secured in such assembled position by means of bolts 16 extending through the flanges 5 and 12 and the body of the sealing strip 6 and clamping the same together 45 into a unitary structure. If for any reason it is desired at any time to remove or repair a roof, this may be easily accomplished by loosening and removing the bolts 16 and elevating the roof panel as a unit from the car.

50 For stiffening the roof panel, it may be provided with any desired number of ribs or channels 17 extending transversely thereof as indicated in dotted lines in Figure 1. Such reinforcing means may conveniently be in the form of 55 inverted channels 18 adapted to receive nailing strips 19 held in position by suitable fastening means 20. As is customary in the art, these nailing strips 19 will preferably terminate above the bottom of the sealing strips 6 an appreciable distance, thereby affording fastening means, similar 60 in function to those now utilized, for the attachment of the head liner or inner roof cover.

The roof structure of Figures 1, 2, 3 and 8 may 65 be preferred in many cases due to the fact that it may be formed from a single sheet of metal having the proper over-all dimensions. It is, however, open to the objection that the flanges 12 must be separately welded in position. In 70 Figures 4, 6, 6a and 6b, there is illustrated a modified form of roof panel construction in which parts corresponding to those heretofore described are designated by the same reference characters having a prime affixed thereto. In this embodiment of the invention, the inner flange 12' is formed integrally with the roof 75

panel 15' by utilizing a blank 21 such as that illustrated in Figure 6. With such a blank, the chain line 22 illustrates the bending line adapted to form the corner 23 of Figure 4; the chain line 24 indicates the bending line along which the sheet is bent to form the reverse bend 25, and the chain line 26 indicates the bending line along which the sheet is bent to form the corner 27. The portions 28 of the blank form the peripheral portions 29 of the finished roof which overlie the sealing strip 6' and the lip 9'.

When the blank is bent into its final shape along the lines 22, 24 and 26, the angularly arranged portions 30 thereof form the square corners 31 of the flanges 12', while the inclined portions 32 meet along the line 33, Figure 6a, to form a corner joint in the finished panel. With such a blank, added strength is insured by reason of the fact that the downwardly projecting flange 12' is of double thickness. Such a construction further gives increased resiliency in a roof structure since the inner and outer portions of the compound flanges 12' may move slightly toward and away from each other to the limit permitted by the bolts 16'. For sealing and partially concealing the joint between the portions of the compound flanges 12', I may utilize a flexible sealing material 34 of suitable plastic nature.

In case it is desired to obviate a seam line in the roof panel and still avoid the expense incident 105 to the welding of the inner flange in position, I may utilize a construction as illustrated in Figures 5, 7, 7a and 7b wherein reference characters corresponding to those used in described Figures 1, 2, 3 and 8, but having a double prime affixed thereto, are utilized. With this form of the invention the roof blank 35 is formed to provide a bending line 36 adapted to form the 110 transversely bent edge 37 as illustrated in Figure 5, and the bending line 38 to provide the right angle 115 bend 39 of Figure 5.

The cut-away portion 40, when the blank is bent to shape, forms a 45° meeting line 41, as shown in Figure 7a, while the angularly extending portions 42 meet to form the joint 43 between the longitudinally and transversely extending flange portions 12''. In this construction the peripheral portion 9'' of the roof panel is of double thickness and the flange 12'' of single thickness. The double thickness of the peripheral portion of the roof panel gives added strength 120 at the edge thereof and forms a smooth peripheral edge insuring an attractive finish.

With all forms of my invention the entire roof is constructed of metal adapted to have a finish 130 applied thereto similar to the finish applied to the remainder of the car, and thus giving to the roof itself an appearance comparable to that of the car body. The life of the roof and the strength thereof are correspondingly increased.

135 My invention has for a further advantage greater ease of manufacture and assembly of the roof structure, with greater ease of roof removal and replacement in case repairs or substitutions are required.

140 With all of the forms of the invention herein illustrated, the sealing strip forming the joint between the quarter panels and the roof panel, and serving to absorb weaving of the roof or car, compensating for differences in expansion and contraction of the different parts of the car structure, and sealing the joint between the quarter panels and the roof panel, also underlies the metallic portions of the roof and the quarter 145 panels.

panel in such manner that possibility of injury to the car occupants is minimized.

While I have herein illustrated and described certain preferred embodiments of my invention, it will be understood that changes in the construction, arrangement and location of the parts may be made without departing either from the spirit of my invention or the scope of my broader claims.

10 I claim:

1. In combination with a car body, a metallic roof therefor, and a rubber shock absorbing and compensating means between said roof and said car body, said rubber means being substantially L-shaped in cross-section, one portion of the L being relatively thicker than the other portion.
2. In a vehicle body roof, the combination with quarter panels extending upwardly from the body defining a roof opening, a roof sheet overlying

said opening, a flange extending downwardly from said roof sheet, and a rubber filler spacing the roof sheet and its flange from the edge of the opening, said filler being of sufficient thickness to compensate for weaving and shock, and for expansion and contraction of the roof sheet and body.

3. A roof for vehicle bodies having quarter panels extending upwardly therefrom forming a roof opening, comprising a continuous roof sheet overlying said opening and having a flange depending thereinto, and a rubber sealing member between the flange and the edge of the opening, said member being of such thickness and elasticity as to absorb without excessive strain the shocks incident to weaving of the body and the expansion and contraction of the roof sheet and body.
